INTERLOCKING SYSTEM FOR RAILROADS

Sedgwick N. Wight, Rochester, N. Y., assignor to
General Railway Signal Company, Rochester,
N. Y.

Application May 28, 1931, Serial No. 540,596

30 Claims. (Cl. 246—134)

This invention relates to interlocking systems for railways, and more particularly to a system in which all of the interlocking is accomplished by electrical isolation.

In interlocking traffic controlling devices in an interlocking system it is not only necessary to so interlock these various traffic controlling devices that conflicting routes cannot be set up, but it is also necessary, or at least expedient, to so interlock the various control circuits that if a particular route has once been set up this route cannot be disturbed by operating levers tending to set up a conflicting route until the lever governing the set-up route has been returned to its normal stop or no-route position, and in accordance with the present invention it is proposed to so organize the circuits that the proceed signal or signals of a particular set-up route cannot be put to stop by levers of conflicting routes. Another feature of the present invention resides in the provision of means for preventing the clearing of a signal if any of a plurality of control devices operating sequentially to control a switch machine associated with such signal assume non-corresponding positions. Another feature of the present invention resides in the provision of control means for switch machines which is only effective if the switch machine is in condition for operation at the time a lever is operated to cause such operation even though the lever is left in such operated position. Another feature of the present invention resides in the provision of route circuit portions which conform precisely with the various portions of the track layout, so that as a route is set up mechanically in the track rails, a corresponding route may be set up electrically in the route circuit portions, thus resulting in an exceptionally simple route circuit organization especially in a complicated track layout, this because the number of contacts in the interlocking circuit organization is directly proportional to the number of switches in the interlocking system. Another feature of this novel route circuit organization resides in the provision of means for setting up a particular direction of traffic over the route represented by the route circuit effective to prevent the setting up of traffic in the opposite direction over such route. Another feature of the present invention as shown in a modified construction resides in the provision of wholly circuit interlocking means for obtaining the necessary and desired safety in the interlocking system, and in the provision of supplemental mechanical lever locking means

to aid the operator against operating a lever which should not be operated.

One feature of the present invention is to so organize the switch machine control in its cooperation with the signal control that a signal cannot be cleared unless the switch control line circuit is intact at the time of such signal clearing. This is accomplished in accordance with the present invention by providing that the switch machine control relay be normally energized both when the signals are at stop and when the signals are at clear, and cause the clearing of such signals to be dependent upon the continued energization of such relay. This is more particularly accomplished by the including of a neutral contact on such switch control relay in the control for the signal circuits, and also by shifting the switch control relay from its control circuit to a stick circuit when a signal is cleared.

This feature has been shown in my later filed copending application Ser. No. 689,109, filed September 12, 1933, in which I am claiming all of the subject matter which is common with regard to the above mentioned feature.

Other objects, purposes and characteristic features of the invention will in part be obvious from the accompanying drawings and will in part be more specifically pointed out hereinafter.

In describing the invention in detail reference will be made to the accompanying drawings, in which:—

Fig. 1 shows a simple interlocking system involving only a single track switch and four associated signals embodying the present invention;

Fig. 2 shows in a schematic manner a more complicated interlocking system and the manner in which the signals thereof are controlled through the medium of the novel route circuit;

Fig. 3 shows how the switch machine lever of the system shown in Fig. 1 may be electrically locked; and

Fig. 4 shows how the circuits of Fig. 3 may be modified, if desired.

Referring to Fig. 1, although the various devices may be housed in any suitable manner, it is proposed and it is believed expedient to house the apparatus shown within the dotted rectangle DO conventionally illustrating the interlocking office, and to house the remaining apparatus exclusive of the switch machines and signals and their associated devices in a field station 55.

or sub-tower as conventionally illustrated by the dotted lines ST.

In the track layout shown, the track rails 10 have been shown divided by insulating joints 11 into isolated sections for track circuiting purposes, of which the track circuits containing the detector track relay DT and the battery 12, the track circuit including the main track relay MT and a battery 13, and the side track circuit 10 including a track relay TT and a battery 14, only have been shown. The track switch S for diverting traffic into the diverging route is preferably controlled by a switch machine SM, which for convenience has been illustrated conventionally without specifically showing its mechanism or operating motor.

The main track signal 20 governs traffic from left to right over the track switch S on the main track, the low speed signal 21 governs east bound traffic, from left to right, into the diverging route, the signal 22 governs west bound traffic on the main track, and the signal 23 governs west bound traffic off of the diverging route. The switch machine SM is directly controlled by 25 a two-position mechanical stick or permanent magnet stick master relay MR. This master relay MR is controlled jointly by the control relay Z and the master auxiliary relay MA. The switch machine repeater relay WP repeats 30 in the sub-tower ST the position of the track switch S, providing that this track switch S is in correspondence with the position of the master relay MR. The normal signal control relay NWP and the reverse signal control relay RWP are controlled jointly by the control relay Z and 35 the switch machine repeater relay WP, these relays NWP and RWP being only energized one at a time if the relays Z and WP assume corresponding positions.

40 The lock relay L locks the control relay Z against operation and in turn locks the switch machine SM against operation. This lock relay L may be controlled in any suitable manner so long as it locks the switch machine SM against 45 operation when it is improper to operate the associated track switch S, namely when a route has been cleared over this track switch or a route set up over this track switch has been accepted by a moving train, but preferably this lock relay L is controlled in a manner as a 50 similarly designated lock relay in the prior application of R. M. Phinney Ser. No. 463,940, filed June 26, 1930, is shown controlled.

In this sub-tower ST are also located for each 55 signal a route relay and a signal relay. The route relay for the signals 20 and 21 have been designated 20-21RR, the signal relay for the signal 20 has been designated 20G and the signal relay for the signal 21 has been designated 21G. 60 Similarly, the signal relay and route relay for the diverging route signal 23 have been designated 23G and 23RR, respectively. Similarly, the signal relay and the route relay for the main track signal 22 have been designated 22G 65 and 22RR, respectively.

70 Referring now to the interlocking tower DO attention is directed to the fact that a miniature track layout corresponding in every respect to the actual track layout is reproduced in the interlocking tower, with the switch machine levers located directly below the track switch, and the signal control buttons or switches preferably located directly in the tracks or routes conventionally representing the track layout. The 75 button or key for controlling the signals 20 and

21 has been designated 30-31. The key for controlling the signal 22 has been designated 32 and the key for controlling the signal 23 has been designated 33. Also, the switch machine lever for controlling the track switch S has been 5 designated SML; this switch machine lever SML has also associated therewith a lockout lamp LO, a transit light TL and a track circuit occupancy light TR.

Operation of Fig. 1.—Attention is directed to 10 the legend associated with the switch machine lever SML signifying that the contacts of this lever are preferably contacts of the snap-acting type, and cannot be held in an intermediate position, and that they move rapidly from one 15 extreme to the other extreme position upon movement of the lever. As shown the control relay Z and the indicating relay K are energized and included in the same series circuit which may be traced as follows:—beginning at 20 the positive terminal of the battery 35, wire 36, snap-acting contact 37, wire 38, lower winding of the relay K, wire 39, polar contact 40 of the relay WPP, line wire 41, front contact 42 of the lock relay L, wire 43, winding of the relay 25 Z, wires 44, 45 and 46, to the midpoint of the battery 35. Attention is directed to the fact that deenergization of the lock relay L will not effect deenergization of the relay Z, but will effect de-energization of the relay K, the relay Z being 30 maintained energized through the following stick circuit:—beginning at the positive terminal of the battery 47 located in the sub-tower ST, wire 48, polar contact 49 of the relay Z, wire 50, back contact 42 of the relay L, wire 43, winding of 35 the relay Z, wire 44, connected to the midpoint of battery 47.

Attention is also directed to the fact that if the lever SML is operated while the lock relay L is deenergized and the relay K is deenergized, 40 subsequent energization of the lock relay L will not result in the control of the relay Z by the lever SML. This is true because the relay K is a stick relay and cannot be picked up unless the position of the lever SML corresponds to the 45 position of contact 40 of the relay WPP, this switch machine repeater relay WPP of course assuming the position corresponding to that of the track switch S, as more particularly described hereinafter. In other words, moving the 50 lever SML, and leaving it in its moved position, will not result in operation of the switch machine if this lever SML was operated at the time the switch machine SM was locked against movement through the medium of the lock 55 relay L.

Let us now assume that the operator moves the lever SML to a dotted position with the lock relay L energized. Under this condition the quick snap action of the contacts of the lever 60 SML will prevent dropping of the relay K, the direction of the turns of the winding being such that the direction of magnetic flux in the relay K is not reversed, which relay K is now included in series with the relay Z through the medium 65 of its stick contact 51, the relay Z being reversed by the flow of current due to this reversal of the lever SML. This operation of the relay Z will of course effect reversal of the polar contacts 52, 53 and 54 of the relay Z, and with the contact 54 out of correspondence with the contact 55 of the master relay MR, the master auxiliary relay MA will be energized through a circuit readily traced in the drawings, and will result in closure of its contact 76. This completes the 75

circuit for the master relay MR to effect operation of this master relay MR to its dotted position, in which position the contact 55 thereof again gets into correspondence with the contact 54 of the relay Z, thereby again effecting deenergization of the auxiliary relay MA and the opening of its contact 26, resulting in deenergization of the master relay MR. The net result is, that the circuit for the master relay MR is closed just long enough to result in its operation, after which this operating circuit is again broken.

Movement of the master relay MR to its dotted position, will of course result in completion of the reverse circuit R of the switch machine SM, thereby effecting operation of the switch machine SM to its take-siding position. The moment the master relay MR was operated to its dotted position the circuit for the switch machine repeater relay WP was broken, this because the master relay MR was then out of correspondence with the point detector contacts 56 and 57, and resulted in the relay WP being deenergized. This relay WP will of course remain deenergized until contacts 56 and 57 again come into correspondence with the contact 58 of the master relay MR, which will occur when the switch machine SM has completed its operating stroke. Also, operation of the control relay Z to its dotted position, as heretofore explained, causes the contact 52 thereof to get out of correspondence with the contact 60 of the relay WP, thus resulting in deenergization of the relay NWP, the relay RWP also remaining deenergized. One or the other of these relays NWP or RWP will become energized through a circuit readily traced in the drawings just as soon as the relays Z and WP again assume corresponding positions.

The polar contact 61 of the relay WP will apply current to a switch machine repeater relay WPP, located in the interlocking office DO of a polarity corresponding to the position of the switch repeater relay WP, providing of course that the detector track relay DT is energized and its contact 63 is closed.

It is thus seen that the switch machine repeater relay WPP is energized when the detector track circuit is unoccupied, providing the master relay MR is in correspondence with the point detector contacts 56 and 57 of the switch S, so that the back contact 64 of the relay WPP may signify in the interlocking office DO this condition of the traffic controlling devices in the field by illuminating one or the other of the transit lights TL or TR, these lamps being further selected by the contacts 65 of the stick relay K. This relay K is deenergized during track occupancy but is energized during the transitory period of switch machine operation, so that the transit light TL and the track occupancy light TR will be illuminated at the proper time. Also, since the locked condition of the switch machine SM is indicated by deenergization of the stick relay K, the back contact 66 of this relay K may be used to illuminate the lock-out lamp LO, as indicated. If desired, the position of the track switch S may be distinctively indicated through the polar contact 67 of the relay WPP.

Having now explained how the switch S may be operated to the diverging route position, how the transitory condition of the switch is indicated by the transit light TL and track occupancy is indicated by the lamp TR, how the switch machine locked condition is indicated by the lamp LO, let us observe how the various signals 20,

21, 22 and 23 are interlocked through route circuits which are built up out of various circuit elements combined in various combinations.

Let us assume that the normal relay NWP is energized and the reverse relay RWP is deenergized, as illustrated in the drawings, and let us assume that the operator wishes to set up east-bound traffic (moving from left to right) on the main track, and in order to do so operates his signal key 30-31 to a circuit closed position. Since the route relay 20-21RR is deenergized the closure of the key 30-31 will result in closure of the following pick-up circuit for the stick relay 20-21SS:—beginning at the terminal (+) of the suitable battery, key 30-31, wire 70, winding of the relay 20-21SS, wires 71 and 72, back contact 73 of the relay 20-21RR, to the other terminal (—).

It should be noted that the relays 20-21RR and 22RR are connected in a closed series circuit, conveniently called a route circuit, but that the two ends of this circuit are normally connected to the same terminal of the battery, namely the minus terminal. Closure of the circuit for the relay 20-21SS, just traced, will effect energization of this relay 20-21SS and closure of its stick circuit through the medium of its stick contact 74 and wire 74a will maintain it energized and will further effect lifting of its contacts 75, 76, 77, 78 and 79. Lifting of contact 75 will reverse the polarity of current applied to this contact 75, thereby energizing the series circuit including the route relays 20-21RR and 22RR, which may be traced as follows:—beginning at the terminal (+) of suitable way station source, front contact 75 of the relay 20-21SS, wire 80, winding of the relay 20-21RR, wire 81, front contact 82 of the relay NWP, wire 83, winding of the relay 22RR, wire 84, back contact 85 of the relay 22SS to the other terminal (—) of said source.

Picking up of the relay 20-21RR opens its contact 73 and closes its contacts 87 and 88. Energization of the relay 22RR opens its contact 89 and effects closure of its contact 90. It will be noted, that the opening of contact 89 of the relay 22RR prevents the stick signal control relay 22SS from being picked up by operation of the signal key 32. Also, opening of contact 73 of relay 20-21RR would prevent picking up relay 20-21SS if it were not already up. In other words, if a route circuit has once been energized by energization of a stick signal relay at one end of such route circuit, the stick signal relay located at the other end of this route locking circuit is rendered incapable of changing the condition of the route circuit.

The circuits for the various signals, such as the signals 20, 21, 22 and 23 are so organized that its signal control stick relay, such as the 60 stick relay 20-21SS, 22SS or 23SS, and its associated route relay, such as, 20-21RR, 22RR or 23RR, must be both energized before the signal in question can be cleared. For instance, in connection with the signals 20 and 21, of which 65 the operator is attempting to clear the signal 20, said signal 20 cannot be cleared unless both the relays 20-21SS and 20-21RR are both energized, as is now the case (see contacts 76 and 87 of these relays).

The signal control relay 28G is now energized through the following circuit:—beginning at the terminal (+), front contact 92 of the detector track relay DT, wire 93, front contact 94 of the relay NWP, wire 95, front contact 96 of the main

track relay MT, wire 97, front contact 81 of the route relay 20-21RR, wire 98, front contact 76 of the stick relay 20-21SS, wire 99, winding of the relay 20G, wire 100, front contact 77 of the relay 20-21SS to the other terminal (-). With the signal 20G energized, the signal 20 is cleared through the circuit including the front contact 104 of relay 20G and the wire 102. It should be noted that with relay 20-21SS deenergized the relays 20G and 21G are short-circuited through wires 68 and 69 respectively. This is done to protect against accidental energization of these relays, as by foreign currents. Attention is directed to the fact that relay 21G for controlling the signal 21 cannot now be energized because the front contact 104 of the relay RWP, signifying the position of the track switch, is open. Also, operation of the signal key 2 will produce no effect, in that the circuit for the relay 22SS controlled thereby is open at the back contact 69 of the relay 22RR, and operation of the key 33 for controlling the signal 23 is ineffective even though this key will effect energization of the signal stick relay 23SS, the contact 105 of the relay 23RR still being closed. Lifting of the contact 106 of this relay 23SS will produce no result, because the circuit for the relay 23RR is open at the front contact 107 of the relay RWP. Putting it in different words, the various elements of the various route circuits may be combined to establish route circuits through the medium of contacts signifying the position of the track switches, and with a route circuit once established, the elements of route circuits which have not been included in the established route circuit, or circuits, will be ineffective and will maintain the associated signals at stop, and the elements which have been combined to establish a route circuit enable only a signal at one end of such route circuit to be cleared, this because if the signal relay at one end of the route circuit is energized it will lock the signal relay at the other end of this route circuit against energization. Although the signals 20, 21, 22 and 23 may be either two-condition or three-condition and may be either light signals or semaphore signals, and may be controlled in accordance with traffic conditions in any suitable way, they have been shown conventionally as controlled by track relays of the track circuits in advance. For instance signal 21 is shown controlled through front contact 103 of signal relay 21G, which relay 21G is in turn controlled through front contacts 78, 88, 86, 104 and 92 of relays 20-21SS, 20-21RR, TT, RWP and DT respectively. Signal 22 is controlled through front contact 136 of signal relay 22G, which relay 22G is in turn controlled through front contacts 137, 90, 138 and 139 of relays DT, 22RR and 22SS, respectively. Also signal 23 is controlled by relay 23G through its front contact 140, which relay 23G is controlled through front contacts 93, 141, 142 and 143 of relay DT, 23RR and 23SS, respectively.

In order to avoid complication in illustrating an interlocking system embodying the present invention, the invention has been shown applied to a rather simple track layout in Fig. 1 of the drawings, but to more clearly illustrate how the novel route circuits may be applied to a more complicated track layout without any material complication in the route circuits themselves, a route circuit having a more complicated interlocking feature has been illustrated in Fig. 2 of the drawings.

Referring to Fig. 2 of the drawings, which illustrates a portion of or an entire interlocking system including signals 1, 2 and 3 for governing east bound traffic into such interlocking system and including signals 4, 5, 6 and 7 for governing west bound traffic into the interlocking system, a cross-over 110 and track switches 111, 112 and 113 having been illustrated to set up various routes. Routes may therefore be set up as follows:—signal 1 to signal 4, signal 1 to 10 signal 5, signal 2 to signal 4, signal 2 to signal 5, signal 3 to signal 4, signal 3 to signal 5, signal 3 to signal 6 and signal 3 to signal 7, and traffic may of course be set up in either direction over each of these routes. Levers L¹, L², L³, L⁴, L⁵, L⁶ and L⁷ have been illustrated to control the signals 1 to 7, inclusive, respectively. Similarly, each of the levers has associated therewith a signal stick relay SS having an exponent corresponding to the number of the signal it controls, resulting in relays SS¹, SS², SS³, SS⁴, SS⁵, SS⁶ and SS⁷. Similarly, each signal stick relay has associated therewith a route relay, these route relays being designated RR with an exponent corresponding to the number of the signal associated therewith, resulting in route relays RR¹, RR², RR³, RR⁴, RR⁵, RR⁶ and RR⁷.

It is desired to point out now, that it is necessary to have both the signal stick relay SS and the route relay RR for a particular signal energized before such particular signal can be cleared, this feature is illustrated in Fig. 2 but has been more fully pointed out in connection with the drawings in Fig. 1. By looking at the track layout in Fig. 2 of the drawings, it will be noted that two routes are set up as illustrated by the track rails and switch box contacts in the drawings, the first route extending from the signal 2 to signal 5, and the second route extending from signal 3 to signal 7.

It should be noted that route circuits corresponding to these track routes are now closed, these route circuits may be traced as follows:—(1) beginning at the terminal (-) of a suitable way station battery, back contact 115 of the relay SS², wire 116, winding of the relay RR², wire 117, switch box or switch position contact 118 (indicating the position of the switch 111), wire 119, contact 120 (signifying the position of the cross-over 110), wire 121, contact 122 (signifying the position of the switch 112), wire 123, winding of the relay RR³, wire 124, contact 125 of the relay SS⁵ in its retracted position, to the same terminal (-) of the battery; and (2) beginning at the terminal (-) of the way station battery, back contact 126 of the relay SS³, wire 127, winding of the relay RR³, wire 128, contact 129 (signifying the position of the track switch 113) wire 130, winding of the relay RR⁷, wire 131, back contact 132 to the same terminal (-).

It should now be noted that for the route leading from signal 2 to signal 5 either the signal 2 or the signal 5 may be cleared by moving the corresponding signal lever and picking up the corresponding signal stick relay, but that as soon as one of these stick relays is picked up the pole changing contact of this stick relay will apply energy to the route locking circuit thereby picking up the route locking relays RR² and RR⁵, thus resulting in locking the other stick relay against energization, all in a manner as already explained in connection with Fig. 1 of the drawings. In other words, traffic can only be set up

in one direction over an established route, and with a particular route once established all of the route locking relays of conflicting routes will be open-circuited. For instance, in the particular track layout illustrated, and with the routes 2-5 and 3-7 set up, the route locking relays RR¹, RR⁴ and RR⁶ are open-circuited at the contact 118, 122 and 129, respectively.

It should further be noted that the particular routes that have been established cannot be disturbed by signal levers of conflicting route signals if the contacts 129, 118, 135, 120 and 122 are switch box or point detector contacts, and these switches are locked against movement, also, it should be borne in mind that the various switch machines for operating the track switches and cross-over are locked against movement if traffic has been set up over such particular track switch or cross-over, as has already been explained and is accomplished by relay L. The net result is, that if a route has once been set up and a signal has been cleared over such route, this signal cannot be put to stop by any lever except that lever used for controlling such signal. Or in other words, the progress of train movement over a selected route which has been cleared cannot be disturbed by a lever of a conflicting route, in spite of the fact that the levers of such conflicting signals or routes are not locked against movement.

Let us now assume that the switches 112 and 113 and the cross-over 110 are all operated to their dotted position, in which event a route extending from signal 3 to signal 4, or from signal 4 to signal 3, is established. This particular route conflicts with all other possible routes, so that only one route can now be set up instead of two routes, as was the case heretofore. Under this assumed condition of the track layout, the route relays RR¹, RR², RR⁵, RR⁶ and RR⁷ have their circuits open at the respective contacts 118, 120, 122, 135 and 129, respectively. One of the advantages of the novel route locking circuit organization shown in Figs. 1 and 2 resides in the fact that only a single contact for each switch is necessary even though such track switch is common to a large number of routes, so that a comparatively simple and inexpensive wiring installation is necessary irrespective of the complication of the track layout, and further that the route circuit organization is such that if a particular route circuit is energized from one end thereof the other end thereof is locked against interference with the first control, and vice versa.

Although the various track switches 111, 112 and 113, the cross-over 110, and the signals 1 to 7, inclusive, in Fig. 2 have been shown rather conventionally, it is desired to be understood that each of the track switches 111, 112 and 113 and the cross-over 110 are preferably operated by suitable switch machines in the same manner as shown in Fig. 1, each of these switch machines being at times locked against operation by a suitable lock-out relay as also shown in Fig. 1. Furthermore, each of the signals 1 to 7, inclusive, are preferably controlled in the same manner as are controlled the signals in Fig. 1 of the drawings, the detail circuit organization for each signal having been omitted from Fig. 2 for convenience and to avoid confusion, as is also true of the various switch machines which have been omitted from Fig. 2. In other words, if the interlocking system conventionally shown

in Fig. 2 were illustrated in detail the lock relay for the switch machine for operating the track switch 112, for instance, would at times depend for its control on signal 1 and at other times on the fact whether signal 2 is clear or at stop, depending upon the position of the track switch 111, and at other times would depend upon the fact whether the signal 3 is at stop or proceed depending upon the position of the cross-over 110 and the track switch 113, all in a manner as clearly understood from the prior application of R. M. Phinney to which reference has been heretofore made. What has been said about the lock relay for switch 112 is also true of the lock relay for the track switches 111 and 113 and for the cross-over 110. In other words, Fig. 2 represents a complete interlocking system involving three track switches, a cross-over and seven signals of the two or three aspect type, together with all of the control circuits and route circuits to interlock the various signal switches and cross-overs to establish the various routes heretofore pointed out in detail, from which the switch machines and their control circuits as well as the control circuits for the signals have been omitted for convenience.

In Fig. 3 has been shown a modified portion of the system shown in Fig. 1. In this modified form of the invention a lever lock comprising an electromagnet 150 for operating the locking pawl 151 has been added to the lever SML³. As shown, the electric lever lock 150-151 is controlled through the front contact 66³ of the stick relay K³, this relay K³ corresponding in every respect to the relay K of Fig. 1 of the drawings. This lever lock 150-151 is not provided to afford additional safety, but is merely added to afford additional facility, or rather to avoid an operator operating a lever when this lever should not be operated. As has already been explained in connection with Fig. 1 of the drawings the lever SML should never be operated when the relay K is deenergized, for such operation of the lever SML, even though it can do no particular harm, will result in no operation of anything except the lever itself, but it could possibly confuse the operator in that he might expect the distant switch S to respond thereto. As already explained, the lever SML if operated when the relay K is deenergized, must after energization of the relay L be returned to its previous position to effect reenergization of the relay K. In the arrangement shown in Fig. 3 the lever SML³ is locked immediately upon deenergization of the relay K³, so that the operator cannot operate the lever SML³ during the locked condition of the switch machine.

From a study of the arrangements shown in Fig. 3 of the drawings it will readily appear that the polar contact 40³ of relay WPP³ and the stick contact 51³ of the relay K³ perform substantially the same function that the electric lock 150-151 performs, in that each of these devices prevents the application of energy to the line wire 41³ when the lock relay L is deenergized. Consequently, if it is desired to rely on the protection afforded by the lever lock 150-151 the polar contact 40³ and the stick contact 51³ may be dispensed with, and such an arrangement has been illustrated in Fig. 4 of the drawings. Also, if desired, the contacts 65⁴ and 66⁴ may be contacts of the relay L in which case the relay K may be omitted.

Applicant has thus shown several embodiments of his novel interlocking system, and has shown rather specific circuits and devices for carrying out the functions of his system, but it is desired 5 to be understood that the specific system illustrated has not been selected for the purpose of showing the scope of his invention, nor has it been selected for illustrating the precise construction necessarily employed in practicing the 10 invention, but has been illustrated for the purpose of facilitating disclosure of the underlying principles of the invention and the manner in which these principles may be applied to a particular track layout, and that various changes, 15 modifications and additions may be made to adapt the invention to the particular problem encountered in practicing the same, all without departing from the spirit or scope of the invention, except as demanded by the scope of the 20 following claims.

What I claim as new is:—

1. In an interlocking system, the combination with a track lay-out including a track switch and a cross-over to establish a plurality of track 25 routes, contacts associated with said switch and cross-over said contacts having circuit closing positions corresponding to the positions of their track points, wires connecting said contacts to establish route circuits corresponding to track 30 routes established by said track switch and cross-over, a signal at each end of each track route, an interlocking contact at each end of each route circuit normally connected to one terminal of a source of current but movable to 35 connect with the other terminal of said source, a route relay near each end in each route circuit, a stick relay for operating said contact and having a pick-up circuit including a back contact of the associated route relay, whereby 40 only the interlocking contact at one end of said route circuit can be operated from normal, and a control circuit for the associated signal including in series a front contact of the associated stick relay and the associated route relay.
- 45 2. In an interlocking system of the electrical isolation type, the combination with a track lay-out including a track switch, a plurality of signals for governing traffic in both directions over the two routes establishable by said track 50 switch, a switch machine for operating said track switch, lock-out means for preventing operation of said switch machine, a circuit including a lever operated contact for controlling a relay for in turn controlling said switch machine and permitting control of said relay only if the act of closure of said contact occurs when 55 said lock-out means is inactive, an indicating relay for indicating the position of said switch machine and whether it is in correspondence with its control relay, three route circuit portions, and two route circuits for interlocking said signals each including two of said route portions and a contact of said indicating relay.
- 60 3. In an interlocking system of the electrical isolation type, the combination with a track lay-out including a track switch, a plurality of signals for governing traffic in both directions over the two routes establishable by said track switch, a switch machine for operating said 65 track switch, lock-out means for preventing operation of said switch machine, a circuit including a lever operated contact for controlling a relay for in turn controlling said switch machine and permitting control of said relay only if the 70 act of closure of said contact occurs when said

lock-out means is inactive, an indicating relay for indicating the position of said switch machine and whether it is in correspondence with its control relay, three route circuit portions, and a contact operated by said track switch for connecting said circuit portions to establish route circuits each corresponding to the track route then established.

4. In an interlocking system of the electrical isolation type, the combination with a track lay-out including a track switch, a plurality of signals for governing traffic in both directions over the two routes establishable by said track switch, a switch machine for operating said track switch, lock-out means for preventing operation of said switch machine, a circuit including a lever operated contact for controlling a relay for in turn controlling said switch machine and permitting control of said relay only if the act of closure of said contact occurs when said lock-out means is inactive, an indicating relay for indicating the position of said switch machine and whether it is in correspondence with its control relay, three route circuit portions each corresponding to a track portion isolatable by said track switch, a contact operated by said track switch for connecting said circuit portions to establish route circuits each corresponding to the track route then established, a lever for each circuit portion thus resulting in a lever for each end of each route circuit, and means for rendering the lever at one end of a route circuit ineffective upon operation of the lever at the other end of such route circuit.

5. In an interlocking system, route control 35 means comprising, a circuit including contacts which assume positions corresponding to the positions of associated track switches, a route relay at each end in said circuit, means for energizing said circuit from each end, and means 40 for preventing de-energization of said circuit from one end if it has been energized from the other end.

6. In an interlocking system, a route control 45 means comprising, a circuit including contacts assuming positions corresponding to the positions of associated track switches, a route relay at each end in said circuit, contacts for energizing said circuit from each end, a signal associated with each end of each route circuit, and interlocking means including the route relays of 50 said circuit for allowing operation of the contacts at one end at one time only and for allowing clearing of the signal only at that end of said circuit.

7. In an interlocking system, route control 60 means comprising, a circuit including contacts assuming positions corresponding to the positions of associated track switches, a route relay at each end in said circuit, means for energizing said circuit from each end, a stick relay associated with each route relay, a signal associated with each route relay, and interlocking means including the route relays of said circuit and the associated stick relays for allowing 65 energization of said circuit at one end at a time only and for allowing clearing of the associated signal at that end of said circuit only.

8. Route control means for interlocking 70 systems comprising, a circuit connecting two route relays and including said relays in series, interlocked means for allowing energization of said circuit from one end at a time only, a signal associated with each of said route relays, and means for allowing clearing of only that signal 75

associated with the route relay at the end at which the energization of said circuit is accomplished.

9. Route control means for interlocking systems comprising, a circuit connecting two route relays and including said relays in series, interlocked means for allowing energization of said circuit from one end at a time only, a signal associated with each of said route relays, a stick relay associated with each route relay and having a front contact for energizing said route circuit and having included in its energizing circuit a back contact of the associated route relay, a signal for each route relay, and a clearing circuit for each signal including a front contact of the associated route relay and front contact of the associated stick relay in series.

10. A route circuit for allowing traffic on a railway system to move in one direction over a particular route only comprising, a line wire having a first relay at each end said first relays being connected in series, a second relay associated with each of said first relays and for energizing said line wire from the corresponding end, and contacts on such first relay for rendering such second relay ineffective to energize said line wire upon energization of such first relay unless such second relay has already energized said line wire.

11. Route control means for allowing railway traffic to move in one direction only over a particular route comprising, a route circuit connecting opposite ends of a route, a first relay at each end in said route circuit for manifesting the energized condition of said route circuit, said first relays being at all times included in series in said circuit, a second relay at each end of said route for energizing said circuit from the corresponding end, and means for interlocking said first and said second relay at each end of said route to prevent said circuit from being changed from that end if it has been energized from the other end.

12. Route control means for allowing railway traffic to move in one direction only over a particular route comprising, a circuit connecting opposite ends of a route, a first relay at each end of said route for manifesting the energized condition of said route, said first relays being at all times included in series in said circuit, a second relay at each end of said route for energizing said circuit from the corresponding end, and a circuit for each of said second relays including a back contact of the associated first relay.

13. Route control means for allowing railway traffic to move in one direction only over a particular route comprising, a route circuit connecting opposite ends of a route, a first relay at each end of said route for manifesting the energized condition of said route circuit, said first relays being at all times included in series in said circuit, a second relay at each end of said route for energizing said circuit from the corresponding end, a circuit for each of said second relays including a back contact of the associated first relay, and a contact on each of said second relays included in said route circuit.

14. A route circuit for allowing traffic on a railway system to move in one direction over a particular route only comprising, a line wire having contacts included therein manifesting that said particular route has been set up and having a first relay at each end, said first relays being connected in series, a second relay as-

sociated with each of said first relays and for energizing said line wire from the corresponding end, and contacts on such first relay for rendering such second relay ineffective to energize said line wire upon energization of such first relay unless such second relay has already energized said line wire.

15. Route control means for allowing railway traffic to move in one direction only over a particular route comprising, a route circuit having contacts included therein manifesting that said particular route has been set up and connecting opposite ends of a route, a first relay at each end in said route circuit for manifesting the energized condition of said route circuit, said first relays being at all times included in series in said circuit, a second relay at each end of said route for energizing said circuit from the corresponding end, and means for interlocking said first and said second relay at each end of said route to prevent said circuit from being changed from that end if it has been energized from the other end.

16. Route control means for allowing railway traffic to move in one direction only over a particular route comprising, a circuit having contacts included therein manifesting that said particular route has been set up and connecting opposite ends of a route, a first relay at each end of said route for manifesting the energized condition of said route, said first relays being at all times included in series in said circuit, a second relay at each end of said route for energizing said circuit from the corresponding end, and a circuit for each of said second relays including a back contact of the associated first relay.

17. Route control means for allowing railway traffic to move in one direction only over a particular route comprising, a route circuit having contacts included therein manifesting that said particular route has been set up and connecting opposite ends of a route, a first relay at each end of said route for manifesting the energized condition of said route circuit, said first relays being at all times included in series in said circuit, a second relay at each end of said route for energizing said circuit from the corresponding end, a circuit for each of said second relays including a back contact of the associated first relay, and a contact on each of said second relays included in said route circuit.

18. In combination, a plurality of routes over a railway system each including a plurality of track switches, a route circuit for each route including contacts assuming positions corresponding to the positions assumed by said track switches in the corresponding route, a signal relay located at each end of each route circuit and included therein so as to be energized when such route circuit is energized from the opposite end, a second relay associated with each signal relay, front contacts on each of said second relays for energizing its route circuit from its particular end, and means preventing the energization of such second relay to close said front contacts when its associated route circuit has already been energized from the other end.

19. In combination, two signals governing traffic in opposite directions over the same track, a line circuit extending from one to the other of said signals, a signal relay associated with each of said signals for when energized permitting clearing of such signal, a second relay associated with each of said signal relays, front

ccncts on each of said second relays for energizing said circuit from its end, and means for preventing the energization of such second relay to close said front contacts when said circuit has 5 already been energized from the other end.

20. In combination, a section of railway track including a track switch, power operating means for the track switch, manually controlled means for governing the operation of said power operating means, indication means for indicating the position of said track switch and its correspondence with said manually controlled means, a route circuit for each route through said section including contacts of said indication means, a 10 signal relay located near each end of each route circuit and energized when such circuit is energized, a second relay associated with each signal relay, contacts on each of said second relays for energizing its route circuit from its particular end, 15 means preventing the control of said energized route circuit by said second relay at the opposite end while such route circuit is energized, and means preventing operation of said manually controlled means when any route circuit is 20 controlled means when any route circuit is 25 energized.

21. In combination, a section of railway track including a track switch, a switch machine for operating the switch, a control relay for controlling the operation of said switch machine, a 30 control lever for controlling said control relay, an indicating relay for indicating the position of the track switch and its correspondence with said control relay, route circuit portions conforming to the track section and track switch 35 layout, means including contacts of said indication relay to complete route circuits corresponding to the mechanical route then set up, a route relay located at each end of each route circuit and included therein so as to be energized when 40 such route circuit is energized, a signal lever repeating relay associated with each route relay for energizing when actuated by its lever any route circuit in which its route relay may then be included, means for preventing the actuation 45 of a signal lever repeating relay when its associated route relay is energized by the signal lever repeating relay at the opposite end of the then completed route circuit, a signal for each signal lever repeating relay and its associated route 50 relay and controlled jointly thereby, and means preventing the response of said control relay to said control lever when a route circuit including contacts of said indication relay is energized.

22. A route circuit for allowing traffic on a 55 railway system to move in one direction only over a particular route comprising, a line circuit having a first relay at each end in said circuit said first relays being connected in series in said circuit, a second relay associated with each of 60 said first relays and for energizing said line circuit from the corresponding end, contacts on each of said first relays open when each such first relay is energized for rendering the associated second relay ineffective to initially energize said line circuit, and a signal controlled 65 by each of said first relays, said signals governing traffic in opposite directions over said particular route.

23. In combination, a stretch of railway track 70 including a track switch, a signal at each end of said stretch for governing the movement of traffic into said stretch from that end, power operated means for operating said track switch, switch control means for controlling said power 75 operated means, a circuit portion closed only

when said switch control means and said power operated means assumes corresponding positions, a traffic governing relay for each of said signals which must be energized to permit clearing of such signal, a route circuit between said traffic 5 governing relays and including said circuit portion, one terminal of a current source connected at each end of said route circuit for supplying potential of one polarity to said circuit, manually controlled means for disconnecting one of said 10 terminals and connecting another terminal of said source to said circuit to energize one of said route relays whereby a plurality of route circuits include the same contacts, and a particular route circuit cannot be closed unless said 15 switch control means and said power operated means assume corresponding positions.

24. In combination, a stretch of railway track including a track switch, a signal at each end of said stretch for governing the movement of 20 traffic into said stretch from that end, power operated means for operating said track switch, independent and manually governable switch control means for controlling said power operated means to thereby operate said track switch 25 to normal and reverse positions, a circuit portion closed only when said switch control means and said power operated means assume corresponding positions, a route circuit extending from one to the other of said signals and including said circuit portion, one terminal of a source of current connected to each end of said route circuit for supplying current to said route circuit to clear one only of said signals at one time, a manually controlled relay for disconnecting said terminal and connecting the other terminal of said source to said circuit to energize said circuit, whereby a plurality of route circuits include the same contacts and a particular route circuit cannot be closed unless 30 said switch control means and said power operated means assumes corresponding positions.

25. In combination, a stretch of multiple railway track including a plurality of track switches, a signal at each starting point of track routes 45 over said track for governing the movement of traffic into such route from that end, separate power operated means for operating each track switch, switch control means for controlling each power operated means, a circuit portion for each switch closed only when the switch control means and its associated power operated means assumes corresponding positions, a traffic governing relay for each of said signals which must be energized to permit clearing of such signal, a route circuit between said traffic governing relays and including a circuit portion for each switch in such route, one terminal of a current source at each end of said route circuit for supplying current to said circuit but normally 50 ineffective, manually controlled means for disconnecting one of said terminals and connecting the other terminal of said source to said circuit, whereby said route circuit cannot be closed unless each switch control means and its power 55 operated means assume corresponding positions.

26. In an interlocking system, a track layout including a track switch, signals for governing traffic in both directions over said track switch in both of its positions, a switch machine for 70 operating said track switch, a control lever for controlling the operation of said switch machine, locking means for preventing operation of said switch machine when any of said signals are cleared, three route circuit portions each cor- 75

- responding to a track portion isolatable by said track switch, contact means operated in accordance with the position of said track switch for connecting said circuit portions to establish route circuits each corresponding to the track route then established, a signal lever for each end of said route circuits for energizing an established route circuit from its end, means preventing a signal lever from either energizing or deenergizing an established route circuit which is energized from the opposite end, and means for clearing the signal corresponding to that end of a route circuit at which such route circuit is energized dependent upon said signal lever for that end and dependent upon the energization of such route circuit. 5
27. In an interlocking system, a track layout including a track switch, signals for governing traffic in both directions over said track switch in both of its positions, a switch machine for operating said track switch, a switch control relay for controlling the operation of said switch machine, a switch control lever for governing said control relay, locking means for preventing control of said switch control relay by said lever when any of said signals are cleared and for permitting control of said switch control relay by said lever only if the actuation of said lever occurs while said signals are at stop, three route circuit portions each corresponding to a track portion isolatable by said track switch, contact means operated in accordance with the correspondence between said track switch and said switch control relay for connecting said circuit portions to establish route circuits each corresponding to the track route then established, a signal lever for each end of said route circuits for energizing an established route circuit from its end, means preventing a signal lever from either energizing or deenergizing an established route circuit which is energized from the opposite end, and means for clearing the signal corresponding to that end of a route circuit at which such route circuit is energized dependent upon said signal lever for that end and dependent upon the energization of such route circuit. 10
28. In combination, two route relays, a route circuit connecting said route relays in series, a stick relay associated with each route relay and having a front contact for energizing said route circuit from its end, a pick-up circuit for each of said stick relays including a back contact of its associated route relay, a stick circuit for each of said stick relays independent of the condition of any route relay, and means controlled jointly by each of said stick relays and its associated one of said route relays. 15
29. In combination; a first group of route relays; a second group of route relays; circuit means for selectively connecting route relays of said first group in series with route relays of said second group in different combinations to form route circuits, each of which includes two route relays; a stick relay associated with each of said route relays in both said groups, each stick relay having a front contact for energizing any route circuit in which its route relay may be connected, 20 a pick-up circuit for each of said stick relays including a back contact of its associated route relay, a front contact of each stick relay for shunting out said back contact of its respective route relay, and means responsive to the picking up of a route relay only when its associated stick relay is picked up. 25
30. In combination; a first group of route relays; a second group of route relays; circuit means including a plurality of independently 30 operable contacts for selectively connecting route relays of said first group in series with route relays of said second group in different combinations to form route circuits, each of which includes two route relays; a stick relay associated with each of said route relays in both said groups, each stick relay having a front contact for energizing any route circuit in which its route relay may be connected, a pick-up circuit for each of said stick relays including a back 35 contact of its associated route relay, a front contact of each stick relay for shunting out said back contact of its respective route relay, and means responsive to the picking up of a stick relay only when its associated route relay is 40 picked up. 45

SEDGWICK N. WIGHT.

DISCLAIMER

2,027,569.—*Sedgwick N. Wight*, Rochester, N. Y. INTERLOCKING SYSTEM FOR RAILROADS. Patent dated January 14, 1936. Disclaimer filed June 8, 1937, by the assignee, *General Railway Signal Company*.

Hereby enters this disclaimer by disclaiming from claim 20 any system, except wherein the "signal relay located near each end of each route circuit" is responsive to the energization of the route circuit so that both of the signal relays are "energized when such circuit is energized"; and by disclaiming from claims 23 and 25 any system, except wherein the "traffic governing relay for each of said signals" is responsive to the energization of the "route circuit between said traffic governing relays", so that both of these relays are energized when such route circuit is energized.

[*Official Gazette June 29, 1937.*]
